SIGNALING APPARATUS

Arthur Cyril Webb Aldis, Sparkhill, Birmingham, England, assignor to Aldis Brothers Limited, Sparkhill, Birmingham, England

Application March 2, 1942, Serial No. 433,086
In Great Britain September 30, 1940

8 Claims. (Cl. 177—327)

This invention has for its object to provide an improved signaling apparatus whereby military or other signals can be transmitted with greater secrecy than is possible with ordinary signaling apparatus.

The invention comprises a telescope adapted both to view a distant station and to project a light beam to that station, and having light deflecting means adapted to be moved to either of two positions for enabling the station to be viewed or the light beam to be projected.

The invention also comprises the combination with the telescope, of a photo-electric cell or other light-responsive means adapted to be actuated by light signals received by the telescope.

Further the invention comprises apparatus as defined in either of the preceding paragraphs and having a vibratory light-reflective or refractive element responsive to sound vibrations and adapted so to modify the transmitted light signals that the latter when received by a distant instrument can be converted into sound vibrations.

In the accompanying sheets of explanatory drawings:

Figures 1, 2 and 2a are respectively a sectional side elevation, an end elevation, and a fragmentary plan of the signaling apparatus constructed in accordance with the invention.

Figures 3 and 4 are sections taken respectively on the lines 3—3 and 4—4 of Figure 1.

Figure 5 is a section on the line 5—5 of Figure 3.

Figures 6 and 7 are detail views illustrating in plan some of the parts shown in Figures 1, 3 and 4.

Figure 8 is a diagram illustrating electrical connections of the apparatus shown in Figures 1 to 7.

Figures 9, 10 and 11 are respectively a fragmentary sectional end elevation, a fragmentary side elevation, and a fragmentary sectional plan, illustrating a modified form of the invention.

Figures 12 and 13 are respectively a fragmentary sectional side elevation and a fragmentary sectional plan illustrating another modified form of the invention.

Figure 14 is a section on the line 14—14 of Figure 12.

Figures 15 and 16 are respectively a sectional side elevation and a part sectional end elevation illustrating to a considerably larger scale than Figures 12 and 13 the vibratory element and associated parts of the example shown in the latter figures.

Figure 17 is a section on the line 17—17 of Figure 16.

In carrying the invention into effect as shown in Figures 1 to 8, I employ a tubular body *a*, having at one end an object lens *b*, and at the other end a holder, or housing *c*, for a light source *d*, in the form of an incandescent filament electric lamp. At any convenient intermediate position the body *a* is provided with a tubular branch *e* mounted at any convenient angle to the body. At the outer end of the branch *e* I mount an eye piece *f* having lenses *g* associated with it, and adjacent to the inner end of the eye piece I mount within the branch *e* a light stop *h*. Also 10 I mount erecting lenses *i* within the branch *e* at any convenient distance from the inner side of the light stop *h*. Moreover within the body *a* and at or near its junction with the branch *e* I mount a member *j* (herein termed a light deflecting member) by which light entering the body through the object lens *b* can be deflected through the erecting lenses *i* and eye piece *f*. The light deflecting member *j* may have the form of a prism as shown, or it may be formed 15 by mirrors or by any other convenient reflecting device, but in any case it is movable in the manner hereinafter described to and from a service position in which it can intercept and deflect light entering the body *a* through the object lens *b*. 20 Between the light deflecting member *j* and the erecting lenses *i* the branch *e* is provided with another light stop *k*, and on or near this stop may be mounted a graticule *m*. Alternatively the graticule *m* may be arranged between the erecting lenses *i* and the eye piece *f*.

Also in the body *a* near its junction with the branch *e*, and between the light source *d* and the service position of the light deflecting member *j*, there is mounted a light stop *n* having a 25 small aperture at *o* at the focus of the object lens *b*, and between this stop and the light source there may be mounted in the rear end of the body any convenient condensing lens *p*. Further in association with the side of the stop *n* nearest to the light source *d* I mount a shutter *q* which is 30 movable under the control of an adjacently situated electromagnet *r* or plunger *s* (Figure 8) to and from a position in which it obstructs the passage of light from the said source to the small aperture at *o*.

When the light deflecting member *j* is in its service position it enables a distant station to be viewed or signals to be received. When it is required to send a signal the light source *d* is 35 brought into action, and the light deflecting

member *j* is moved laterally to an out-of-service position clear of the light beam projected by the said source through the small aperture at *o* under the control of the shutter *q*.

The electric lamp forming the light source *d* is preferably provided with a cylindrically coiled filament *t* which can be brought into an oblique position on the optical axis of the object lens *b* and thereby present an incandescent surface devoid of any non-luminous gaps to the small aperture at *o* when the latter is uncovered by the shutter *q*, any convenient means (not shown) being provided for enabling the lamp to be mounted in the holder or housing *c* with the filament accurately located in the desired position.

For enabling the light deflecting member *j* to be moved laterally to and from its service position, the tubular body *a* is provided at the position where it is joined by the branch *e* with a rectangular or other enlargement *u* in which the light deflecting member is mounted on a slide *v*, the latter being slidable on guide bars *w* carried by a plate *x* which serves to close the side of the enlargement remote from the branch, and which is removably secured in position by screws or other fastenings. In one extreme position of the slide *v* the light deflecting member *j* occupies its service position, and in the other extreme position of the slide the said member occupies its out-of-service position, the extreme positions of the slide being determined by abutments *y* at the ends of the guide bars *w*.

Situated at one side of the light deflecting member *j* is a shaft *z* which extends longitudinally through and is rotatably supported by the enlargement *u* of the body *a*, and on an axis parallel with this shaft there is rotatably supported by the slide *v* a member *2* through which movement can be imparted to the slide by an arm *3* extending radially from the shaft, the latter and the said member being formed with transverse holes for slidably accommodating the adjacent ends of the arm. On this arm *3* is mounted a helical spring *4* which at one end bears against the member *2* carried by the slide *v*, and at the other end bears against a collar *5* on the arm, the collar being caused by the spring to bear against the adjacent side of the shaft *z*. At one end the shaft *z* carries a finger lever *6*, and by appropriate movement of this lever the shaft can be turned for moving the slide *v* between its extreme positions, the first part of each such movement being effected by the arm *3* against the action of the spring *4* which after passing a dead centre position completes or assists the arm in completing the said movement and then serves to hold the slide against accidental movement.

The shutter *q* above mentioned is arranged in the body enlargement *u* at the end remote from the object lens *b*, and this shutter has the form of a blade secured to and projecting from one side of a pivotal carrier *7*, the latter being movable by the electromagnet *r* for actuating the shutter. The carrier *7* is supported at a position intermediate its ends by a knife-edge bearing *8* on a bracket *9* which also carries the winding *10* of the electromagnet *r*, and which is secured to the plate *x* forming the removable side of the body enlargement *u*. When the electromagnet winding *10* is de-energised the shutter *q* occupies a position in which its free end covers the small aperture at *o* in the stop *n*, and obstructs the passage of light from the source *d* to the said aperture. A spring *11* acting on the shutter carrier *7* serves to hold the shutter *q* in the above

mentioned position which is determined by contact of the carrier with an adjustable stop *12* on the bracket *9*. When the winding *10* is energised the electromagnet *r* serves to move the carrier *7* against the action of its loading spring *11* to a position in which the free end of the shutter *q* uncovers the small aperture at *o* in the stop *n*, and allows light from the source *d* to be projected through this aperture.

As shown in Figure 8 the circuit of the electromagnet winding *10* contains any convenient source of current supply, such as a battery *13*, and is controlled by a signalling key *14*. Also the circuit of the light source *d* may contain, in addition to a battery *15* or other source of current supply and a main control switch *16*, another switch *17* which is movable by or concurrently with the light deflecting member *j* so that the light source is in action only when the light deflecting member is in its out-of-service position. The switch *17* may consist of a pair of fixed contacts *18*, and a movable contact *19* adapted to bridge the fixed contacts, the movable contact being conveniently carried by the underside of the slide *v* as shown in Figure 4, and the fixed contacts being carried by and insulated from the plate *x* (forming the removable side of the body enlargement *u*) as shown in Figures 4 and 7. In this case the plate *x* also carries terminals *20* through which current can be supplied to that part of the light source circuit which contains the fixed contacts *18*.

Electric current is supplied to the winding *10* of the electromagnet *r* through terminals *21* also carried by the plate *x*. If for any reason the supply of current to the winding *10* fails, the shutter *q* can be actuated by the above mentioned plunger *s* which extends through and is slidably supported by the wall of the body enlargement *u* at a position opposite to the electromagnet *r*. At its outer end the plunger *s* is provided with a push button *22* whereby it can be actuated against the action of a loading spring *23*, the inner end of the plunger being adapted to act on the shutter carrier *7*.

When remote control of the shutter *q* is not required the electromagnet *r* may be dispensed with, in which case the plunger *s* is used to actuate the shutter.

When used for locating or receiving signals from a distant station the apparatus above described forms a telescope, the light deflecting member *j* being in its service position. To enable signals to be transmitted to a distant station, the light deflecting member *j* is moved to its out-of-service position and the light source *d* is brought into action. Morse or other signals can now be transmitted by suitable actuation of the key *14*, this causing a narrow beam of light to be projected intermittently from the light source *d* through the small aperture at *o* and thence through the object lens *b*.

If it is desired to impart colour to the projected light beam any convenient coloured screen *25* may be arranged in the path of this beam. For enabling this to be effected a holder *24* adapted to carry a plurality of coloured screens *25* is arranged within and extends transversely across the body enlargement *u* at a position between the light deflecting member *j* and the object lens *b*. At one end this holder *24* is carried by a sleeve *26* freely mounted on the end of the above mentioned shaft *z* remote from the finger lever *6*, and on the sleeve is mounted another finger lever *27*. By appropriate manipulation of the

finger lever 27 the holder 24 can be adjusted about the axis of the shaft 20 to bring any one of the screens 25 into the path of the light beam above-mentioned, a spring-loaded detent 28 on this finger lever serving by alternative engagement with recesses 29 in the adjacent side of the body enlargement *u* to retain the holder in its adjusted positions.

As the apparatus above described is particularly suitable for sending and receiving signals at night any convenient means, such as a small lamp 30 may be mounted on the body enlargement *u* for illuminating the graticule *m*. Also a small blue window 31 may be provided in the holder or housing *c* in which the light source is mounted, this window appearing black when the light source is out of action, and blue when the light source is in action.

To prevent internal reflection of light in the apparatus above described the whole of the interior of the apparatus may be painted dead black. Also the part of the tubular body *a* between the enlargement *u* and the object lens *b* is provided with a plurality of spaced partitions 32 having central apertures 33 which progressively decrease in diameter from the object lens to the said enlargement, the partitions being spaced apart by helical springs 34, and both the partitions and springs being painted dead black.

At its ends the body *a* is supported by bearings 35 on supports 36 adapted to be mounted on any convenient stand (not shown), the body being rotatably adjustable in the bearings to bring the branch *e* into any desired position suited to the requirements of the observer.

When the apparatus above described is required to receive signals it is necessary for the observer to remain constantly on watch. In order to avoid this necessity I may employ the example illustrated in Figures 9 to 11. In this example I mount on any convenient part of the body enlargement *u* a chamber 37 in which is mounted a photo-electric cell 38 or any other suitable light-responsive means such as a selenium cell. Also I employ in addition to the above described light deflecting member *j* (hereinafter referred to as the first light deflecting member) a second light deflecting member 39 which may have the form of a prism. This second light deflecting member 39 is adapted to be moved laterally to and from a service position on the optical axis of the telescope. When in this position the member 39 serves to deflect the said axis through a right or other convenient angle, and thereby to cause the said axis to pass by way of a small aperture 40 in a light stop 41 into the interior of the chamber 37 containing the cell 38, this chamber being otherwise light-tight. The small aperture 40 is accurately located in the focal plane of the object lens, and in consequence the aperture can be made to correspond to a relatively small area immediately surrounding the distant station. Arising from the fact that the second light deflecting member 39 has only to deflect the focussed image of a flash sent out from the distant station and not the whole field of view of the telescope, the said member can be of small size and placed close to the focal plane of the object lens. Consequently the second light deflecting member 39 can be made to occupy, when in use, a position in the body enlargement *u* between the first-mentioned small aperture at *c* and the service position of the first light deflecting member *j*, so that both light de-

flecting members can be brought to their respective service positions without fouling each other.

The second light deflecting member 39 may be actuated by an electromagnet 42 which may be mounted on the plate *x* closing one side of the body enlargement *u*. As shown this electromagnet comprises a winding 43 and a spring loaded plunger 44, the latter being provided at its outer end with a plate 45 on which the second light deflecting member 39 is mounted, and which is held against rotational movement by the engagement of a peg 46 on the body of the electromagnet with a slot 47 in the said plate.

Instead of being actuated by an electromagnet 42 the second light deflecting member 39 may be rigidly attached to the first light deflecting member *j*, and the two members may be actuated by an external lever adapted to take up any one of three positions corresponding to the second member in action, the first member in action, or both members out of action.

The second light deflecting member 39 may serve to deflect the optical axis through any convenient angle and in any convenient plane as compared with the first light deflecting member *j*. It is however convenient for the two planes of deflection to be mutually at right angles to each other, since with such an arrangement the chamber 37 containing the cell 38 can be mounted in the most suitable position.

By arranging the light responsive means 38 in the manner described above it is very effectively screened from any light from external sources other than from the distant signaling station and objects in its immediate vicinity, which latter can be painted black and shaded from daylight. I have found that this screening of the light responsive means conduces to efficiency in amplifying the minute light impulses received.

The light responsive means 38 is adapted to control a sound producing apparatus, a visible indicator, and/or mechanism for recording the signals as dots and dashes marked on a tape driven by clock work or motor, the said apparatus, indicator, and/or mechanism being mounted either adjacent to the telescope or at some neighbouring receiving station.

From the foregoing it will be seen that the apparatus shown in Figures 9 to 11 is not only adapted to be used in a similar manner to that shown in Figures 1 to 8, but is also adapted to convert the received light signals into audible signals, or signals which are visible otherwise than through the telescope.

The addition of the light responsive means in combination with the means controlled thereby enables a desirable additional advantage to be obtained in that after the telescope has been adjusted on to a distant signaling station, the signals from that station can be rendered audible, or can be seen without looking through the telescope, thus rendering it unnecessary for an observer to give his constant attention to the telescope.

When it is required to transmit oral communication the examples shown in Figures 12 to 17 is employed. In this example I employ any convenient vibratory light reflective or refractive element 48 capable of oscillating in response to a mechanism actuated by sound vibrations. This element may be actuated directly, or by electromagnetic or electrostatic means, in response to the vibrations of a diaphragm or the like which receives the oral messages to be transmitted. The

element 48 is situated between the light source *d* and very close to the small aperture *o* (Figure 15) which, when illuminated by the light source through the interposition of a condenser lens *p*, is responsible for sending out light signals. The housing or holder *c* containing the light source *d* and supporting the condenser lens *p* is situated at one side and near the end of the tubular body *a* remote from the object lens (not shown). Further the vibratory element 48 is placed on the telescope axis between the light source *d* and the small aperture *o* in such a way that, at one particular orientation, all the light which passes through this aperture from the light source is received by the telescope object lens and forms the signaling beam. In addition I employ for masking the object lens a mask 49 having a rectangular aperture 49a whose sides are respectively parallel and perpendicular to the axis about which the vibratory element 48 can oscillate. Moreover I may similarly mask the aperture of the condenser lens *p* which concentrates a spot of light for illuminating the small aperture *o* after refraction or reflection by the vibratory element 48, but preferably I make the aperture of the condenser lens *p* much larger than is needed to fill the object lens with light, and I employ for masking the condenser lens a mask 50 having a straight edge situated parallel to the axis of the vibratory element 48 so that an image of this edge can be caused by the vibratory element to oscillate across the masked down aperture of the object lens. But in either case the arrangement is such that the light transmitted to the telescope object lens through the small aperture *o* is variable according to the orientation of the vibratory element 48, passing from a maximum when the light just fills the object lens to a minimum when hardly any light reaches the object lens at the two extreme ends of the arc of oscillation of the vibratory element. In this way the intensity of the light emitted by the telescope object lens can (by the oscillations of the vibratory element 48) be varied in a manner corresponding to the variations in the sound vibrations which actuate the element.

Oral messages transmitted in the form of light by the apparatus above described are received by the light responsive means of a receiving instrument and thereby re-converted into sound vibrations.

If desired I may provide means for locking the vibratory element 48 in a position in which it transmits maximum light, and employ a shutter for interrupting the beam at a position very close to the small aperture *o* as in the previously described examples, so that the apparatus can serve also for transmitting Morse signaling. Alternatively I can use a Morse key for reversing the current in the circuit of the electrical device (hereinafter described) which serves to oscillate the reflective or refractive element 48, the arrangement being such that with the key depressed the current flows one way and causes the said element to assume a position in which there is maximum illumination of the object lens, and with the key raised the current reverses thereby swinging the said element to a position for causing no light to reach the object lens and no beam in consequence to be emitted, but preferably I employ any convenient valve oscillator for actuating the vibratory element 48 under the control of a Morse key. Thus with this preferred arrangement the telescope when the key is not depressed emits a steady beam at half strength,

while dots and dashes take the form of an oscillatory beam sent out of short or long duration. The steady beam evokes no response from the light responsive element at the receiving end but the oscillatory beam provokes a vigorous response in the form of an oscillatory current which gives rise to a note of corresponding pitch in a loudspeaker or headphones.

When using the apparatus for transmitting messages in Morse the mask 49 is moved to an out-of-service position in the manner hereinafter described, so that the full aperture of the object lens can be used for transmitting signals. The other mask 50 may also be moved to an out-of-service position, but when this mask has its preferred form as indicated above it may be fixed in its service position.

If it is required to lock the vibratory element 48 in the position in which it transmits maximum light for the purpose above described, I can secure this result either by mechanical means, or by passing a suitable steady current through the circuit of the electrical device associated with the vibratory element to bring the latter to the appropriate orientation and to hold it there.

In its preferred form as shown the vibratory element 48 consists of a small mirror carried by and situated in the diametral plane of an oscillatory spindle 51. Formed on or secured to the spindle 51 at a position spaced from the mirror 48 is a steel bar 52 which is situated at right angles to and extends from opposite sides of the spindle. At its ends the bar 52 is situated between rubber cushions 53 which serve to support the bar and spindle whilst permitting vibratory movement thereof about the axis of the spindle. The cushions 53 are secured to and carried by iron pole pieces 54 on the ends of a permanent horse-shoe magnet 55, the pole pieces being bridged by non-magnetic metal strips 56 which serve to secure the cushions in position. The adjacent faces of the pole pieces 54 are shaped to provide at their ends two pairs of pole tips 57 between which the adjacent ends of the bar 52 are situated. Between the pole tips 57 the adjacent faces of the pole pieces 54 are shaped to accommodate bobbins 58 made from electrical insulating material, the bobbins being wound with very fine wire 59 adapted to receive oscillating currents from a microphone, the effect of these currents being to cause oscillatory movements of the bar 52 and spindle 51 about the axis of the spindle. The bobbins 58 surround the bar 52 at opposite sides of the spindle 51, the adjacent ends of the bobbins 58 being in contact with each other, and being shaped to accommodate between them rubber bushes 60 through which the adjacent portions of the spindle extend. The horse-shoe magnet 55, the pole pieces 54, and the bobbins 58 are all made in two halves divided in a medial plane containing the axis of the spindle 51 as shown.

The horse-shoe magnet 55 is secured in a cup-like carrier 61 which at diametrically opposite positions is supported by pivots 62 in a cylindrical housing 63, the pivots being arranged coaxially with the spindle 51. At one end the housing 63 is closed except for the small aperture *o*' which is provided in a light stop in the form of a hollow member *n*' on the said end of the housing, this member being arranged to extend into the housing to bring the said aperture into the required close proximity to the mirror 48. At its opposite end the housing 63 is closed by a removable cover 64 which carries an adjusting screw 65 for determining the position of the carrier 61

within the housing, the adjusting screw being adapted to act on the carrier in opposition to a spring 66 in the form of a bifurcated metal plate carried by the end of the housing remote from the adjusting screw.

The housing 63 is arranged within and adapted to fit the interior of the tubular body *a* at a position near the condenser lens *p*, the removable cover 64 being accessible through the adjacent end of the body after another cover 67 has been removed from this end of the body.

Holes 68 formed coaxially with the condenser lens *p*, in the housing 63, the carrier 61, and the horse-shoe magnet 55, enable light passing through the condenser lens from the source *d* to illuminate the mirror 48 which in turn is adapted to illuminate the small aperture *o* through which the signaling beam is transmitted.

The mask 49 employed for masking the object lens may be made to an elongated form from sheet metal and arranged in a housing 69 forming a part of the body *a* at that side of the body enlargement *u* which is situated nearest to the object lens. At one end the mask 49 is pivotally connected to a cover piece 70 closing one side of the housing 69, and at a position near its other end the mask is provided with the rectangular aperture 49a above mentioned. The cover piece 70 also carries an electromagnet having a winding 71 and a spring-loaded plunger 72, the latter being connected to the pivoted end of the mask 49 by linkage 72a. When the winding 71 is energised the mask 49 is moved by the plunger 72 from its out-of-service position as shown, to a service position for masking the object lens as above described. Return of the mask 49 is effected by the spring loading of the plunger 72 when the winding 71 is de-energised.

The other mask 50 employed for masking the condenser lens *p* is mounted in the interior of the holder or housing *c* for accommodating the light source *d*.

In other respects the example shown in Figures 12 to 17 is essentially similar to that shown in Figures 9 to 11 and differs only in minor constructional details some of which will now be described.

The slide *v* which carries the first light deflecting member *j* consists of a pair of interconnected plates between which the said member is situated, and which is slidably supported on a pair of transverse guide rods *w* in the body enlargement *u*. For actuating the slide *v* to move the first light deflecting member *j* between its service and out-of-service positions, a push-pull rod 73 arranged parallel with the guide rods *w* is connected to one side of the slide and passes through a boss on the adjacent side of the body enlargement *u*, and this boss carries a spring-loaded detent 74 which is adapted by engagement with grooves 74a in the push-pull rod to determine the above mentioned positions of the first light deflecting member. The slide *v* may be adapted to control the electric circuit of the light source *d* as previously described.

The side of the body enlargement *u* remote from that through which the push-pull rod 73 passes is made removable and carries the electromagnet 42 for actuating the second light deflecting member 39, the latter being carried by the plunger 44 of its actuating electromagnet, and being adapted (when in its service position) to deflect the optical axis of the telescope through a small aperture into the interior of a chamber 37 containing a photo-electric cell 38 or other

light responsive means as previously described, this chamber being situated at the side of the body enlargement remote from the branch *e*.

Further the holder 24 for the coloured screens 5 is secured at one end to a short oscillatory spindle 15 which passes through a wall of the body enlargement *u*, and which at its outer end carries a lever 16 whereby the said holder can be adjusted to bring different coloured screens into the path of the signaling beam, the lever carrying a spring-loaded detent 17 which by engagement with recesses in the said wall serves to retain the holder in the desired adjusted positions.

By this invention military or other signals can be transmitted with great secrecy. The invention is not, however, limited to the examples above described as subordinate details may be varied to suit requirements.

Having thus described my invention what I claim as new and desire to secure by Letters Patent is:

1. Signaling apparatus comprising in combination a main tubular member, an object lens arranged at one end of and coaxially with the main tubular member, a branch tubular member united at one end with an intermediate portion of the main tubular member, an eye piece and a light source housing disposed one at the outer end of the branch tubular member and the other in the vicinity of the end of the main tubular member remote from the object lens, light deflecting means, and means for moving the light deflecting means into and out of a service position in which it deflects the optical axis of the object lens through the branch tubular member.

2. Signaling apparatus comprising in combination a main tubular member, an object lens arranged at one end of and coaxially with the main tubular member, a branch tubular member united at one end with an intermediate portion of the main tubular member, an eye piece and a light source housing disposed one at the outer end of the branch tubular member and the other in the vicinity of the end of the main tubular member remote from the object lens, light deflecting means, and means for moving the light deflecting means into and out of a service position in which it deflects the optical axis of the object lens through the branch tubular member.

40 3. Signaling apparatus comprising in combination a main tubular member, an object lens arranged at one end of and coaxially with the main tubular member, a branch tubular member united at one end with an intermediate portion of the main tubular member, an eye piece and a light source housing disposed one at the outer end of the branch tubular member and the other in the vicinity of the end of the main tubular member remote from the object lens, light deflecting means, and means for moving the light deflecting means into and out of a service position in which it deflects the optical axis of the object lens through the branch tubular member, light responsive means arranged at one side of the main tubular member, and a second light deflecting means movable into and out of a service position in which it deflects the optical axis of the object lens on to the light responsive means.

45 4. Signaling apparatus comprising in combination a main tubular member, an object lens arranged at one end of and coaxially with the main tubular member, a branch tubular member united at one end with an intermediate portion of the main tubular member, an eye piece and a light source housing disposed one at the outer end of the branch tubular member and the other in the vicinity of the end of the main tubular member remote from the object lens, light deflecting means, and means for moving the light deflecting means into and out of a service position in which it deflects the optical axis of the object lens through the branch tubular member, and a vibratory element responsive to sound vibrations and operable to deflect light from the housing through the object lens.

50 5. Signaling apparatus as claimed in claim 2 and having a light stop provided with a small aperture through which light from the object

lens can be directed by the second light deflecting means on to the light responsive means.

5. Signaling apparatus as claimed in claim 1 and having within the main tubular member a light stop provided with a small aperture through which light from the housing can pass when the light deflecting means is in an out-of-service position.

6. Signaling apparatus as claimed in claim 1 and having in combination a light stop arranged within the main tubular member and provided with a small aperture through which light from the housing can pass when the light deflecting means is in an out-of-service position, and a shutter for controlling the said aperture.

7. Signaling apparatus as claimed in claim 1 and having in combination a light stop arranged

within the main tubular member and provided with a small aperture through which light from the housing can pass when the light deflecting means is in an out-of-service position, a shutter for controlling the said aperture, and electromagnetic means and hand operable means for alternately actuating the said shutter.

8. Signaling apparatus as claimed in claim 3 and having in combination with the vibratory element, an oscillatory supporting spindle, a housing arranged within the main tubular member, a carrier which is adjustably mounted within the latter housing and in which the vibratory element is supported by the spindle, and means whereby the spindle can be oscillated in response to sound vibrations.

ARTHUR CYRIL WEBB ALDIS.
